UNITED STATES PATENT OFFICE.

WILLIAM E. McCORMICK, OF NEW YORK, N. Y., ASSIGNOR TO MELODELITE CORPORATION, OF NEW YORK, N. Y., A CORPORATION OF NEW YORK.

DESIGN FOR A PORTABLE ELECTRIC LIGHT.

Application filed August 9, 1928. Serial No. 27,752. Term of patent 14 years

To all whom it may concern:

Be it known that I, WILLIAM E. McCORMICK, a citizen of the United States, residing in the city of New York, county of Bronx, and State of New York, have invented a certain new, original, and ornamental Design for a Portable Electric Light, of which the following is a specification, reference being

had to the accompanying drawing, forming a part thereof.

Fig. 1 is a perspective, and Fig. 2 is a front elevation showing my new design.

I claim:

The ornamental design for a portable electric light as shown.

WILLIAM E. McCORMICK.
